UNITED STATES PATENT OFFICE

136,387

DESIGN FOR A MAKE-UP APRON

Helene Pons, New York, N. Y.

Application June 9, 1943, Serial No. 110,415

Term of patent 3½ years

To all whom it may concern:

Be it known that I, Helene Pons, a citizen of the United States, residing at New York city, in the county and State of New York, have invented a new, original, and ornamental Design for a Make-Up Apron, of which the following is a specification, reference being had to the accompanying drawing, forming a part thereof.

Fig. 1 is a plan view of a make-up apron, showing my new design, and in flat, open condition.

Fig. 2 is a front view thereof, as worn on the person.

Fig. 3 is a side view of the apron shown in Fig. 2.

I claim:

The ornamental design for a make-up apron, substantially as shown.

HELENE PONS.
